ATTORNEY.

UNITED STATES PATENT OFFICE

FREDERICK U. CONARD, OF STRATFORD, CONNECTICUT, ASSIGNOR TO UNDERWOOD
ELLIOTT FISHER COMPANY, OF NEW YORK, N. Y., A CORPORATION OF DELAWARE

TYPEWRITING MACHINE

Original application filed February 16, 1929, Serial No. 340,533. Divided and this application filed May 27, 1930. Serial No. 456,056.

This invention relates to improvements in line-space levers for typewriting machines, and more especially to those of the portable type, where conservation of space is of paramount importance, and wherein lightness, accessibility, cheapness and durability are essential. Heretofore, in order to produce portable typewriters as small as possible, platen-knobs have not, generally, been used 10 on the left-hand side of the carriage. One of the features of this invention, therefore, is the provision of such a platen-knob, which is easy of access by the operator and one which does not increase the total width of the 15 machine.

Another feature relates to the novel form and location of the lever which is mounted sufficiently away from the platen-knob so that the latter is accessible and without adding 20 to the extreme dimensions of the machine.

Another feature relates to the process by which the levers are manufactured, whereby the levers may be formed by a cold process 25 of a single piece of metal, making them rugged, strong and durable. One of the advantages of this process lies in the fact that the levers can be made of metals not susceptible to heat treatment as the parts need not be 30 heated to go through these operations. Another advantage of the process for manufacturing the levers is the saving of metal used during this construction, so that the scrap metal is a minimum. The levers are also 35 made of such a shape as to be easily finished by polishing and plating, or otherwise. The levers have no joints, crevices or corners to retain dirt as they would have if made of several separate pieces assembled together.

Portable machines are made as low in 40 height and as compact as possible largely to permit the use of a small carrying case, and, to this end, another feature of this invention is the provision of a finger-piece pivoted to 45 the end of the lever and which extends above

the other parts of the machine and is easily accessible when in use, but which may be turned down against the pressure of a spring by the cover of the carrying case when being closed. This feature greatly reduces the 50 height of the case.

In this invention the left-hand platen-knob occupies the usual position with reference to the platen, but as this location is ordinarily occupied by the line-space lever in portable 55 machines, the lever in this case has been bent upwardly and forwardly, forming an offset in which space formed thereby the knob may be located and where it is readily accessible by the operator. The lever in plan view may be substantially T-shaped, composed of a longitudinal long arm and a lateral short arm across the end of the long arm. The short arm extends both sides of the end of the long arm. One end of the short lateral arm is 60 pivoted to the carriage, while the other end is pivoted to and actuates the line-spacing 65 mechanism of the platen. The free end of the long arm is provided with two integral lugs forming along with a pivot-screw, in part, a bearing for a finger-piece pivoted thereto and which is urged by a spring towards a vertical position. The finger-piece is constructed so that it may be depressed by closing the cover of the case, in which it may 70 be mounted, and which act rocks the finger-piece from a vertical to a longitudinal position, permitting the cover to close. When the cover of the case is raised, the finger-piece automatically raises, by means of the 75 spring, to its vertical operating position, ready for use.

This is a division of my application Serial No. 340,533, filed February 16, 1929.

Other features and advantages will herein- 85 after appear.

In the accompanying drawing,

Figure 1 is a perspective view of parts of 90 a typewriter, having this invention embodied therein.

Figure 2 is a plan view of the spacing lever after it has been blanked out of sheet-metal.

Figure 3 is a side view of Figure 2.

Figure 4 is a view of the lever shown in Figures 1 and 2, after it has been twisted a one-quarter turn.

Figure 5 is a view of the lever shown in Figure 4, after it has been swedged in the forming die.

Figure 6 is a transverse section through Figure 5 and looking in the direction indicated by the arrows 6-6.

Figure 7 is a side view of the lever shown in Figure 5.

Figure 8 is a view of the lever after the raw edges shown in Figure 5 have been trimmed. The raw edges or fins are shown in dotted lines.

Figure 9 is a side view of the lever shown in Figure 8.

Figure 10 is a view of the lever after its arm has been offset.

Figure 11 is a perspective view of the lever in final form, ready to be assembled.

Figure 12 is a plan view of the assembled parts, as shown in Figure 1, illustrating the accessibility of the platen-knob.

Referring to the drawing, a platen 15 is rotatably mounted on a platen-shaft (not shown), journaled in the carriage 16 of the typewriter. The platen 15 has an associated ratchet-wheel 17 secured thereto, which is rotated by a pawl 18, pivotally attached to a slide-bar 19. The pawl 18 is normally disengaged from the ratchet-wheel by a seat 50 secured to the frame of the carriage, so that when the slide 19 moves backward taking the pawl 18 with it, the latter drops into engagement with the ratchet-teeth and rotates the wheel 17 and consequently the platen 15 the desired amount. A spring 20 is attached at one end to a screw 21, and the other end to the carriage, whereby the parts are returned to their initial position, as shown in Figure 1.

The slide-bar 19 is slidably mounted on the carriage 16, actuated by the lever 25, and has a lug 23, into which is threaded the screw 21. The latter has a shank which forms a pivot for the arm 24 on the lever 25. Another arm 26 on the lever 25 is pivoted on the shank of a screw 27, which is threaded into a pivot-block 28 that is attached to the end frame of the carriage. The arms 24 and 26, provided with bosses 29 and 30 having holes 39 and 40, respectively, are all integral with the lever-arm 31. The latter is offset at 32 and 33, Figure 10, to lie in an approximately parallel plane to that of the arms 24 and 26.

With reference to the process of making the lever 25 of one piece of metal, attention is called to the fact that heretofore it has not been possible to swedge side extensions forming lugs similar to 36 and 37 on a lever of this kind without using an excessive

amount of metal, and even then it has only been possible to do so by a hot forging process. In this invention the lever 25 is made by a cold swedging process, as follows. The part that is to become a lever 25 is first punched out of sheet metal, as a blank, which may have a thickness somewhat less than the width of the finished lugs 36, 37.

In the present embodiment of the invention the sheet metal is one-quarter of an inch thick, while the lugs 36 and 37 are five-sixteenths of an inch at the bottom and tapering off toward the top, as shown in Figure 11. This invention is, however, applicable for making levers of many sizes and shapes, and is not limited to any given dimensions. The blank 46, as shown in Figure 2, in this punching operation, is formed with a side projection or terminal 45, Figure 2, at one end thereof, which is later on in the process, to form the lugs 36, 37.

The blank 46 is made with the short arms 24, 26 forming a terminal at the other end. The blank 46 is formed with the portion between the terminals having a slight lateral curve 47. The blank 46 may now be given a twist through ninety degrees between the terminals, as shown at 51 in Figure 4.

The curve 47 in the long arm 31 is so formed in the blank 46 that when the blank is twisted, its lower side will lie approximately in a flat plane, see Figure 4. The twisted blank may now be placed in a suitable swedging die, and, under heavy pressure applied thereto, the metal of the blank is forced into all of the interstices of the die, see Figures 5 and 6.

The surplus metal during the operation extrudes between the members of the die, as a fin 48, which, later on, may be trimmed to form the edges of the lever as desired, as in Figures 8 and 9. During the swedging operation the top of the lever is arched by the die to give it greater rigidity, and, when finished, this arched top 34, Figure 5, presents a pleasing appearance. The lever may be given several swedging operations in the die to harden the metal and make the lever stiffer.

The lug 35 on the end of the long arm 31, thus formed, may be milled across to form two lugs 36 and 37, which form, in part, the hinge for the finger-piece 43. Both lugs 36 and 37 are drilled, and one lug tapped to receive the screw 38, forming the pivot upon which the finger-piece 43 rocks. The finger-piece is provided with two ears 42.

A spiral spring 44 on the pivot-screw 38 tends to retain the finger-piece 43 in its vertical position, shown in Figure 1. The spring 44 yields upon the cover of the case (not shown), being closed upon the finger-piece 43, making it rock downwardly under the cover.

Figure 11 illustrates the lever in its final shape, before being assembled with the finger-piece 43 and other parts, and before mounting in the carriage of the machine.

Figure 12 shows the relation of the platen

knob 49 to the lever 25, looking from the top. From this view it is seen that the long arm 31 of the lever 25 is mounted to the right of the knob 49, so that accessibility to the same 5 is secured.

The finger-piece 43 is curved to form a finger-grip as shown in Figure 1.

To operate the lever disclosed herein for line-spacing, after the cover of the case has 10 been removed and the finger-piece has assumed its vertical position, as shown in Figure 1, the finger of the operator engages the curved finger-piece 43 and presses it to the right. This swings the lever 25 on the pivot-screw 27 and moves the short arm 24 rearwardly. The latter moves the reciprocating slide-bar 19 with it, and also the pawl 18 pivoted thereto. During the first part of 15 this motion the pawl 18 slides off the seat 50 and engages one of the teeth of the ratchet-wheel 17, moving the same through the desired letter-space distance. Continued pressure against the finger-piece 43 moves the carriage to the right of the machine, ready 20 for typing another line. Upon removing the finger from the finger-piece 43, the lever 25 returns, by reason of the pull of the spring 20, to its initial position, taking the slide-bar 19 and the pawl 18 with it, until finally the 25 pawl 18 again engages the seat 50, and is raised thereby out of engagement with the ratchet-wheel 17, thus permitting the free rotation of the platen in either direction by hand, if so desired.

25 The very light line-spacing lever 31 has the advantages of sheet-metal, and has the further object that a pair of integral front ears 36, 37 extend down therefrom. Said ears would be impossible in a sheet-metal lever. 30 The finger-piece 43 is presented between the lever and the hand of the operator, so that the drive of the hand is transmitted through the finger-piece directly against the side edge of the lever, which forms a bearing between 35 36 and 37, the result being the same as if the hand were pressed against the lever directly.

There is no pivoting action of the finger-piece at 38 during the line-spacing operation.

The finger-piece is very small. There is no 40 relative motion of the finger-piece and lever while the machine is in use.

Variations may be resorted to within the scope of the invention, and portions of the improvements may be used without others.

45 Having thus described my invention, I claim:

In an encased portable typewriting machine, the combination with a platen and a platen-frame having an end, of a line-space 50 lever mounted at its rear upon said end and extending forwardly from the platen-frame, and having at its front end a pair of integral pendent ears, one behind the other, the edge of said lever between said ears forming 55 a bearing, and a thin finger-plate standing

alongside of the forward end of said lever, and extending upwardly therefrom, and bearing sidewise directly thereagainst, and serving to operate the line-space lever and return the platen-frame, said finger-plate 70 having at its bottom a pair of ears bent in and housed between the pendent ears upon said line-space lever, and a pintle whereby said finger-plate ears are hinged to said lever-ears, said finger-plate being depressible by the cover of the casing of the typewriter, and having a return spring. 75

FREDERICK U. CONARD.
